Primary Examiner — Marie D. Fast Horse*Assistant Examiner* — Jennifer Sierra Yosinski(74) *Attorney, Agent, or Firm* — Wood Herron & Evans LLP(57) **CLAIM**

The ornamental design for a paper holder, as shown and described.

DESCRIPTION

FIG. 1 is a front left top isometric view of a paper holder showing my new design;

FIG. 2 is a rear left top isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

Elements or portions of the design shown in broken lines show non-claimed aspects of the invention. Neither the broken lines themselves nor the portions represented by the broken lines form any part of the claimed invention.

1 Claim, 7 Drawing Sheets(56)
